Patented June 21, 1921.

FIG. 2.

FIG. 1.

WITNESS

W. Drell.

INVENTOR,
MacArthur Van Deusen

BY
John Deusen,
ATTORNEY.

UNITED STATES PATENT OFFICE.

MACARTHUR VAN DEUSEN, OF MIDLAND PARK, NEW JERSEY; ANNIE P. VAN DEUSEN ADMINISTRATRIX OF SAID MACARTHUR VAN DEUSEN, DECEASED.

TIE ATTACHMENT FOR SHOES.

1,381,950.

Specification of Letters Patent. Patented June 21, 1921.

Application filed August 21, 1919. Serial No. 318,847.

To all whom it may concern:

Be it known that I, MACARTHUR VAN DEUSEN, a citizen of the United States, residing at Midland Park, in the county of Bergen and State of New Jersey, have invented certain new and useful Improvements in Tie Attachments for Shoes, of which the following is a specification.

This invention relates to tie attachments for shoes, and particularly low shoes, and it has for one of its principal objects to provide a tie attachment which will present a neater and more attractive appearance than the ordinary lacing and which will further permit a flat lace to be employed and while used retained with its loops in a flat or otherwise convenient form. Another object is to provide a tie attachment which will include, with a flexible lace arranged in a tie, a stiff back having means for readily securing the attachment to a shoe, as, for example, to the lacing thereof.

In the drawing,

Figure 1 is a plan view of a shoe provided with my tie attachment;

Fig. 2 is a similar view, the lace being omitted and the back *a* being shown partly broken away;

Fig. 3 is a rear elevation of the said back, with a fragment of the lace shown in place thereon;

Fig. 4 is a side elevation of the said back; and

Figs. 5, 6 and 7 are sectional views on lines 5—5, 6—6 and 7—7 of Fig. 3.

The attachment includes a lace arranged in some desirable form of tie, such as that shown in Fig. 1, and a back of stiff material therefor to which the tied lace is serially cured and which maintains it in shape.

In the preferred form of the invention the back, *a*, aforesaid, is constructed as shown best in Figs. 3 to 7. To form this back I take a piece of sheet metal, and form it with a transverse arch from one end to the other, its length being sufficient so as to cover the full complement of lacing eyelets *b* of the low shoe *c*. The longitudinal edge portions of this piece *a* are bent up reversely to the arch thereof, as shown best in Figs. 6 and 7, and in each of the bent up portions is formed a row of apertures *d* each elongated longitudinally of the row. Outwardly of each aperture *d* is thus formed a bar *e*, the outer edge of each bar being preferably convex, as

at *f*, Figs. 3 and 4, as by giving the edge of the piece *a* a fluted form.

With a view to improve the appearance of the shoe and at the same time hide the lacing *g* which is passed through the eyelets *b* and secures the shoe on the foot in the ordinary way, I prefer to use in connection with the piece *a* a tie composed of a lace of the flat or ribbon type, as shown in Fig. 1, arranged preferably to form a series of transverse loops *h*, abutting or approximately abutting on each other, and a bow *i*. The said lace is attached to the piece *a* by threading it through the apertures *d* in some such way as is shown in Fig. 3 so as to produce the flat loops *h* appearing in Fig. 1, and when all of the apertures have been thus threaded by the lace the ends of the latter are formed into the bow *i*. The apertures *d* being elongated, the loops remain flat throughout their full extent, even where they pass through the apertures; otherwise stated, each loop bears flat against two bars *e* and so is kept transversely extended or flat, an effect which will be enhanced if the edge of each bar is convex, as at *f* in Figs. 3 and 4.

The device may be secured over the lacing in any desired way, but I prefer to attach it so that it may be readily applied and removed. Thus, as shown in Figs. 2 to 5, the piece *a* is formed at its lower end with an inwardly rebent tongue or hook *j* to catch in the lowest loop *h* of the lacing *g*, and near the upper end of the piece *a* two pairs of transverse slits *l* are formed, and the material between the slits in each pair is bent inwardly, as at *m*, out of the plane of the piece itself to form an eyelet *n* through which eyelets the ends of the lacing *g* may be passed. After the hook *j* has been engaged in the lacing at *h* and the ends of the lacing passed through the eyelets *n*, the ends of the lacing are tied and may then be tucked in the top of the shoe.

Having thus fully described my invention, what I claim as new and desire to secure by Letters Patent is:—

1. As an article of manufacture, a detachable tie attachment for shoes including, in combination, a flexible flat lace arranged in a succession of flat loops, and a stiff back for the lace having means to receive the respective loops and hold each flat.

2. As an article of manufacture, a detach-

able tie attachment for shoes including, in combination, a flexible flat lace arranged in a succession of flat loops, and a stiff back for the lace having two side-by-side rows of 5 lacing bars each arranged longitudinally of the row, the lace being laced flat around each bar and the several bars thus holding the loops flat.

3. As an article of manufacture, a tie at-

10 tachment for shoes including, in combination, a flexible lace arranged in a succession of loops, and an elongated stiff back for the lace having its opposite edge portions bent up in the same general direction and having means in said edge portions to receive and 15 hold the respective loops.

In testimony whereof I affix my signature.

MACARTHUR VAN DEUSEN.
